UNITED STATES PATENT OFFICE.

BERRY A. BAXTER, OF MANSFIELD, OHIO.

VALVE.

No. 853,621.

Specification of Letters Patent.

Patented May 14, 1907.

Application filed May 27, 1905. Serial No. 262,688.

To all whom it may concern:

Be it known that I, BERRY A. BAXTER, a citizen of the United States of America, and a resident of Mansfield, Richland county, 5 Ohio, have invented certain new and useful Improvements in Valves, of which the following is a specification.

My invention relates to a combination needle valve or lever cock and a regulator and is 10 adapted to be used in the consumption of gases for fuel and light.

It is well known to those engaged in the manufacture of the various devices used in the consumption of gases that it is necessary 15 in order to secure the greatest efficiency and economy to provide a means of regulating the supply and delivery of the gas to the burner to conform to the pressure in the mains, which varies in different localities, ac- 20 cording to the nature of the gas (natural or artificial) and the process used in the manu- 25 facture and delivery to the consumer. Another desirable feature in the construction of a valve is to afford facilities for regulating the admission and flow of the gas to the 30 burner according to the pressure irrespective of the needle valve or lever cock and permitting direct, constant and uniform flow and communication with the burner when the needle valve or lever cock is open.

The objects of my invention are to construct a valve and regulator in such a manner as to provide a means of overcoming the disadvantages incident to the use of the ordinary valves in different localities with varying pressures and to regulate the admission 35 of the gas independent of the needle valve or lever cock.

Another object of my invention is to per- 40 mit the flow and passage of the gas through the valve in such a manner as to deliver it directly into the burner in uniform and proper quantities and at a point where the greatest efficiency of the mixture of gas and air is ob- 45 tained.

A further object is to provide a means of cleaning the valve and its connections that is simple and efficient without removing or disconnecting the burner from the supply pipe.

50 I attain these and other objects by the mechanism illustrated in the accompanying drawing in which the figure is an elevation in cross-section showing the application in detail of my device to an ordinary angular 55 needle valve.

Similar figures refer to similar parts throughout the several views.

Referring to the drawing (1) indicates body portion of an angular valve which is made integral with the regulator (2). An 60 inlet pipe (3) is made integral or connected to the valve with the aperture (4) communicating with the valve chamber (5). The regulator is provided with a screw threaded aperture adapted to receive and engage with 65 the threaded exterior of the regulator needle (6) leaving the tapered end (7) extending into the chamber (8) alined with the seat (9) formed in the end of the reducer (10) and communicating with the orifice (11). The 70 regulator needle can be adjusted to conform to the pressure in the mains. The reducer is movably secured to the hollow screw threaded projecting end (12) of the regulator. An ordinary needle valve stem (13) with a 75 suitable operating wheel (14) having a portion (15) made smaller in diameter with its end (16) tapered is fitted to the inner screw threaded portion of the valve chamber (5) providing a means of adjustment permitting 80 the valve to be opened or closed more or less as desired. The tapered end (16) is adapted to close or partially close the orifice (17) which communicates with and permits the 85 passage of the gas into the chamber (8).

The operation of my device is as follows:— The gas is admitted through the aperture 90 (4) in the inlet pipe thence to the valve chamber (5) and passes through the orifice (17) into the chamber (8) of the regulator. The 95 needle valve is used to shut off or partially close the orifice (17) which in a manner regulates the supply or pressure of gas but in an unsatisfactory manner as the quantity of gas or pressure is increased as the operating 100 wheel is turned to open or close the valve. The regulator obviates the disadvantages and defects incident to the use of the ordinary valve as it is independent of the valve and its mechanism. It will be observed that the regulator pin can be adjusted to permit the flow of more or less gas to the burner according to the pressure or quantity it is desired to use in order to mix properly for combustion irrespective of the pressure or flow in 105 the mains. Especial attention is directed to the fact that the operating wheel or lever which controls the valve can be opened or turned back any number of times without affecting the quantity supply or pressure of the 110

gas as it is regulated by the regulator independent of the valve. If it is desired to clean the orifice in the reducer the pin (6) can be removed with an ordinary wrench and a broomstraw or other article can be inserted in the orifice as the opening is in direct alinement with the regulator chamber, thus it will be observed that it is not necessary to remove the burner in order to clean the orifice as is common in the use of the ordinary valves.

Having thus described my invention what I claim as new and desire to secure by Letters Patent is—

15 The combination of a gas regulator and valve, comprising a body portion with an inlet aperture and a longitudinal portion made integral therewith forming a valve chamber, an inclined passage leading from the inlet ap-

erture in the body portion into the valve chamber, a regulator adjustably fitted to said longitudinal portion, a screw-threaded plug with a reduced aperture formed therein fitted to the open end of said chamber, a tubular portion forming a valve chamber made integral with the body of the valve projecting downwardly at an angle with the body corresponding to the inclined passage, a needle valve having a reduced extremity adjustably fitted to said tubular portion and adapted to close or vary the size of the inclined passage.

Signed at Mansfield, Ohio, this 13 day of May 1905.

BERRY A. BAXTER.
